UNITED STATES PATENT OFFICE.

ROY H. McELROY, OF DAYTON, OHIO, ASSIGNOR TO INTERNATIONAL CLAY MACHINERY COMPANY, OF DAYTON, OHIO.

GAS-BURNER.

1,311,132.

Specification of Letters Patent. Patented July 22, 1919.

Application filed April 21, 1919. Serial No. 291,720.

To all whom it may concern:

Be it known that Roy H. McElroy, a citizen of the United States, residing at Dayton, in the county of Montgomery and 5 State of Ohio, has invented certain new and useful Improvements in Gas-Burners, of which the following is a specification.

This invention relates to new and useful improvements in gas burners of a type 10 adapted to be used in connection with kilns. The primary object of the invention is to provide a gas burner which gives a long flame whereby an even distribution of the heat is secured and the kiln is not damaged 15 from a localization of the heat. Other objects of the invention will be described in the specification and pointed out in the claims.

Referring to the accompanying drawings; 20 Figure 1 is a section through the wall of a kiln showing my improved burner applied thereto; Fig. 2 is a vertical longitudinal section through the burner; Fig. 3 is a section on the line 3-3 of Fig. 2; and Fig. 4. 25 is an end elevation of the burner.

Referring more particularly to the drawings, -1- represents the side wall of a kiln provided with an arch -2-, a bag wall -3- and a burner opening -4-. It is to 30 be understood that the kiln in its entirety comprises a plurality of such portions.

Adapted to extend into the burner opening -4- is the front or discharge end of a burner constructed as follows. The burner 35 consists of an elongated rectangular shell -5- provided at its forward end with a division wall -6-. The wall -6- tapers downwardly and forms an upper passageway -7- which also tapers downwardly, 40 for the air which supports combustion, and a lower passageway -8- for the gas the passage of which is indicated by the arrow, Fig. 2. The shell -5- is provided on its upper side with a thimble -9- which opens 45 into the air passageway -7- and which receives a downtake -10- leading from a header -11- supported by brackets -12- on the side of the kiln. The downtake -10- is provided with a suitable valve -13- and 50 receives air under pressure from the header and delivers it to the burner. The under side of the shell is provided with an opening -14- formed by a thimble -15- provided with a flange -16-. The opening -14- communicates with an uptake

-17- leading from a gas duct -18-. The duct -18- leads from a source of fuel such as a gas producer, it, however being understood, that the burner is adapted for any kind of gas. The flange -16- rests upon 60 a flanged plate -19- which, together with masonry -20-, forms a sand seal -21-. The passage of the gas through the opening -14- and into the burner is controlled by a sliding valve -22- which lies on the 65 bottom portion of the shell -5- and which is provided with an operating handle -23- extending out through the rear end of the burner. To permit the interior of the 70 burner being cleaned, the rear end thereof is provided with a door -24- hinged at -25- and having a recess -26- which receives the handle -23-. The door -24- is also provided with an opening 75 -27-, closed by a suitable plug, and which permits access to be had, by means of a scraper, to the valve -22-, whenever the valve becomes obstructed by the tarry 80 deposits of the gas. The shell -5- is also provided with a similar opening -28- which permits access to be had to the up-take -17-. The shell is also provided with ears -29- with suitable openings by means of which the burner may be elevated 85 and carried to other burner openings of the kiln, it being understood that only enough burners are provided to accommodate those portions or compartments of the kiln being fired.

In a gas burner as thus constructed, the 90 gas receives the air for supporting combustion, on top and at a contracted area; consequently, an extended time will be consumed in mixing the gas and air, which results in an elongated flame and an even 95 distribution of the heat through a large space. Also, the heat is not localized or intensified at any one point, which eliminates deterioration of the kiln and results in a uniform burning of the ware. 100

Having described my invention, I claim;

1. A removable burner for kilns, comprising an elongated rectangular shell the inner end of which has a downwardly and forwardly slanting air passage within the 105 space of the burner adapted to receive air through the top of the burner, and a gas passage in said burner below the air passage, the said air and gas passages discharging into the burner opening in the wall of 110

the kiln, said burner having a gas inlet in the bottom thereof communicating with the gas passage of the burner, said inlet being in communication with the source of gas supply, substantially as described.

2. A removable burner adapted to be connected into any of the burner openings in the walls of the kiln, and consisting of an elongated shell the front end of which is 10 adapted to enter the said burner openings, and the central portion of which is adapted to be supported on the gas tunnel masonry, the front end of said burner so entering said burner openings being provided with a 15 downwardly and forwardly slanting air passage extending through the front end of the burner, the said air passage connecting with a down-take through the top of said burner, and a gas passage extending 20 through the length of the burner, said gas passage and said air passage discharging

into the burner openings of the kiln, and the said gas passage connecting through the bottom of the burner with the gas tunnel formed in the masonry of the kiln, substantially as described.

3. A detachable burner for kilns, comprising an elongated rectangular shell having two forwardly and downwardly tapered walls which provide an air passage in the 25 top of the burner that discharges through the front end thereof, and a gas passage extending through the length of the burner and also discharging through the front end thereof, said burner having an opening in 30 the bottom thereof through which gas is introduced to the passage through the burner, and means on said burner adapted to facilitate the removal of the burner from 35 one opening in the kiln to another.

In testimony whereof I affix my signature.

ROY H. McELROY.
